CLAIM

The ornamental design for a firearm aiming device, as shown and described.

DESCRIPTION

FIG. 1 is a rear, top, left perspective view of a firearm aiming device of our new design;

FIG. 2 is a front, bottom, right perspective view thereof;

FIG. 3 is a top view thereof;

FIG. 4 is a bottom view thereof;

FIG. 5 is a left view thereof;

FIG. 6 is a right view thereof;

FIG. 7 is a rear view thereof; and

FIG. 8 is a front view thereof.

FIG. 9 is a rear, top, left perspective view of another embodiment of a firearm aiming device of our new design;

FIG. 10 is a front, bottom, right perspective view thereof;

FIG. 11 is a top view thereof;

FIG. 12 is a bottom view thereof;

FIG. 13 is a left view thereof;

FIG. 14 is a right view thereof;

FIG. 15 is a rear view thereof; and,

FIG. 16 is a front view thereof.
